UNITED STATES PATENT OFFICE.

MATTHEW MCNEILL, OF ALLEGHENY, PENNSYLVANIA.

DESIGN FOR A BRICK.

SPECIFICATION forming part of Design No. 31,329, dated August 1, 1899.

Application filed April 13, 1899. Serial No. 712,935. Term of patent 14 years.

To all whom it may concern:

Be it known that I, MATTHEW MCNEILL, a citizen of the United States of America, residing at Allegheny, in the county of Allegheny and State of Pennsylvania, have invented a certain new and useful Design for Bricks, of which the following is a specification, reference being had therein to the accompanying drawing.

My invention relates to a certain new and useful design for bricks, and more particularly to that class of bricks employed for building purposes.

In the accompanying drawing is illustrated a perspective view of a brick embracing my design.

In the drawing, 1 indicates the body por-

tion of the brick, which is of rectangular shape and having one of its sides 2 and one of its ends 4 formed in a rounded manner, and also having one corner 3 formed in a like manner and describing a curve and the remaining side and end flat. 20

Having described my invention, what I claim as new, and desire to secure by Letters 25 Patent, is—

The design for a brick, substantially as herein shown and described.

In testimony whereof I affix my signature in the presence of two witnesses.

MATTHEW MCNEILL.

Witnesses:

JOHN NOLAND,
E. W. ARTHUR.
